UNITED STATES PATENT OFFICE.

HENRY WELSCH, OF EL PASO, TEXAS.

EMBOSSING MACHINE.

Application filed February 2, 1922. Serial No. 533,598.

To all whom it may concern:

Be it known that I, HENRY WELSCH, a citizen of the United States, residing at El Paso, in the county of El Paso and State of

5 Texas, have invented new and useful Improvements in Embossing Machines, of which the following is a specification.

This invention relates to embossing machines, and is adapted particularly for use 10 in machines of that character wherein it is required to provide raised or embossed letters, figures or designs upon metallic plates.

The primary object of the invention is to 15 provide an embossing machine of the character stated wherein improved driving mechanism for the embossing rolls or points is employed, and wherein the speed of movement of these rolls is accurately timed during the embossing operation.

20 A further object of the invention is to provide a machine of the character stated embodying means of an improved nature for adjusting and accurately controlling the embossing rolls.

25 A still further object of the invention resides in an improved mounting for the shafts carrying the embossing rolls, whereby the adjustment of such shafts, both longitudinally and angularly, may be minutely 30 carried out.

A still further object of the invention is 35 to provide an embossing machine of comparatively simple construction, which involves but few simple and readily assembled parts, the said parts being so constructed and arranged as to minimize the opportunity for wear or breakage, which permits of a wide range of adjustment of the embossing points or rolls, which may be 40 readily adapted to metallic plates varying in thickness, which involves novel means for maintaining the same rigid at all times, and which will prove thoroughly practical and efficient in use.

45 With these and other objects in view, the invention consists of the features of construction, combination and arrangement of parts, hereinafter fully described and claimed, reference being had to the accompanying drawings, in which:—

50 Figure 1 is a side elevation of an embossing machine constructed in accordance with the invention,

Figure 2 is a top plan view of the improved embossing machine, 55

Figure 3 is a front elevation of the machine,

Figure 4 is a transverse sectional view taken on the line 4—4 of Figure 2,

Figure 5 is a sectional view taken upon 60 line 5—5 of Figure 1,

Figure 6 is a similar view on line 6—6 of Figure 2,

Figure 7 is a detail fragmentary view of the jack employed in maintaining the machine rigidly in position, 65

Figure 8 is an enlarged front elevation of the lower portion of the embossing head with the embossing roll removed therefrom, and illustrating the means for controlling 70 the movement of the work supporting table,

Figure 9 is a side elevation of the device shown in Figure 8,

Figure 10 is a sectional view taken on line 75 10—10 of Figure 9,

Figure 11 is a plan view of the device shown in Figure 9, and

Figure 12 is a fragmentary view taken through the upper embossing head and illustrating the manner in which the forward 80 end of the upper embossing roll shaft is mounted.

The embossing machine of my invention includes a body indicated at 13 formed of 85 cast iron or any other suitable metal of sufficient size and weight to withstand the pressure and strains to which the same must necessarily be subjected. This body includes lower and upper arms or heads 14 and 15 90 disposed in parallel relation, the lower head constituting a base adapted to rest upon a suitable table, platform or other support and having outturned feet 16 at its forward and rear ends, through which suitable bolts 95 or other retaining members may be passed to secure the embossing machine to its platform. The upper and lower head portions of the base are separated by a slot 17 extending throughout the breadth of the base 100 and extending inwardly from the forward end thereof to a point near the rear of the said base. This slot or recess constitutes a throat in which the work is received during the embossing operation. 105

The upper head 15 of the base is provided,

21 inwardly from the forward end thereof, with a socket 18 to receive the lower end of a standard 19 constituting a part of the compression jack shown in Figure 7. The 5 upper end of standard 19 receives the lower end of a threaded stem 20, while the upper end of the said stem engages in a post 21 provided with an enlarged base or flange 22 at its top to engage with a ceiling or other 10 overhead structure. Spaced adjusting nuts 23 are threaded upon the stem 20 between the adjacent ends of standard 19 and post 21, and it is obvious that by manipulation 15 of these nuts pressure in a downward direction may be caused to take place in standard 19 to rigidly and firmly hold the embossing machine in place upon its supporting bench or platform.

The embossing machine includes under 20 and upper shafts 24 and 25, the said shafts having their forward ends terminating at the front end of the base 13, and these adjacent ends of the shafts are equipped with rolls or embossing points between which the 25 plate to be embossed is interposed in operation of the machine. The under shaft 24 is disposed at an angle to the other shaft 25 and is supported at its rear end in a bearing 26 depending from the rear portion of the 30 base or body 13. The forward end of the under shaft extends upwardly through a suitable bearing in the front portion of the under head 14 of the base, and a conventional form of embossing or cutting roll 27 35 is secured in any suitable manner to the said forward end of the under shaft. The shaft 24 is capable of being adjusted longitudinally, and to this end the rear portion of the said shaft is threaded and detachably 40 carries adjusting collars 28. These collars are disposed one upon each side of the bearing 26, it being understood that the interior of the said bearing is unthreaded.

The upper shaft 25 is capable of longitudinal as well as lateral adjustment, and is 45 normally disposed substantially parallel to the kerf or throat 17 and slightly above the same. The rear extremity of this shaft is swingingly and rotatably supported in the bearing member 29 disposed in rear of base 50 13 and preferably formed integral with the latter. This bearing 29 has pivoted therein a sleeve 30 mounted for swinging movement upon the ends of pins 31 55 extending inwardly from bearing member 29 at diametrically opposite points therein. The rear portion of the shaft 25 is threaded as shown and carries internally threaded collars 32 one disposed upon each 60 side of the bearing sleeve 30. It is apparent, therefore, that longitudinal adjustment of the shaft may be made by manipulating the collars 32.

The forward end of the shaft 25 is journaled in a block 33 mounted for vertical

adjustment in the forward end of head 15. To this end, the forward end of the head is recessed, as shown particularly in Fig. 12, and slidably receives the said block. The opposing sides of the block 33 are provided with vertically disposed channels 34 which receive the inner ends of steady pins 35 carried by the head, and the upper portion of block 33 is swiveled in the lower end of an adjusting rod or screw member 36. The member 36 extends upwardly through the head 15 and is provided at its upper extremity with a hand wheel 37 having a grip 38 thereon. From this construction it is apparent that rotary movement developed in 80 the threaded shaft 36 will cause the block 33 to be raised or lowered, depending upon the direction of rotation of the said shaft. The forward end of the shaft 25 is provided with a cutting or embossing head 39 for co-operation with roller 37 upon the under shaft.

A main power shaft 40 is rotatably mounted in bearings 41 arranged in spaced relation above the base or body 13, and to the 90 rear end of this shaft is secured a gear 42 in mesh with a gear 43 secured to the shaft 25 near the rear end thereof. The gear 43 meshes with a gear 44 carried by the rear extremity of the under shaft 24. The main 95 power shaft is provided at its forward end with a hand wheel 45, by means of which rotation of shaft 40 may be manually governed. The teeth of gears 42—43—44 are so constructed as not to become disengaged 100 from or bound with each other in the several adjustments of the shafts. It is apparent, therefore, that rotary movement developed in shaft 40 will be transmitted to gear 43, and this motion will in turn be delivered 105 to gear 44, whereupon the shafts 25—24 will be caused to rotate, irrespective of the angles at which the same may be disposed.

The forward end of the lower head 14 is provided with a vertically adjustable work 110 supporting table 50, which is adapted to co-operate with the shaft adjustments in properly presenting the work to the embossing rolls. This table is attached near its forward end to the upper end of an adjusting shaft 51, the said shaft being swiveled to the table 50 as shown. The shaft 51 is supported in suitable bearings 52 at the forward end of the lower head 14, and is threaded 115 engaged by a finger nut 53 maintained between a pair of the said bearings. The table carries an angular offset extension 54 at one side, having a vertically disposed slot 55 therein, through which extends a locking pin 56 having a wing nut 57 on the outer end thereof. The inner end of this pin 120 threadedly engages in the head 14, and an expansion spring 58 is interposed between the head and the angular extension 54. It is apparent that by loosening the threaded 125

member 56 and rotating the finger nut 53, the table 50 may be raised or lowered, and when the desired adjustment has been attained, tightening of the nut of the bolt 56 5 will cause the table to be firmly locked in its position of adjustment.

In operating the embossing machine, the ends of shafts 24—25 will be provided with embossing rolls of the proper type to perform 10 the work at hand, and the upper shaft 25 and table 50 will be adjusted to properly accommodate and operate upon the work. The metallic plate to be operated upon will have outlined thereon, as by pencil, chalk 15 or crayon, the design, symbol, number or figures to be embossed, and the operator inserts the work between the rolls so that the adjacent edges of the latter will properly aline with the symbol outlined upon 20 the plate. This may be done by rotating hand wheel 37 so as to lift the forward end of shaft 25, and after the work has been inserted and properly centered, the said shaft is moved downwardly by retrograde 25 movement of the adjusting wheel. The rolls are then operated by turning wheel 45, this action creating rotation in each of shafts 24 and 25. The operator moves the plate or work so that the outline 30 of the symbol or figure upon the plate will pass properly between the embossing points, as will be understood. This operation will continue until the entire series of letters, numbers or symbols upon the plate have 35 been embossed, whereupon the plate may be removed and such other finishing touches applied thereto as required, such as painting, and embellishing the outline or raised parts upon the plate. The character or 40 thickness of the plate to be operated upon will determine the degree of adjustment of plate 50, as well as the character of the embossing rolls 27—39 to be applied to the shaft ends, and it will be understood that 45 the machine will be provided with an assortment of cutting or embossing rolls for a proper operation upon all types of work and in outlining varied forms of designs.

Machines of this character are commonly 50 of very heavy and cumbersome construction, so made in order to adapt the upper arm or head 15 to withstand the strains of more or less heavy work, under which said arm is liable to be forced upward, causing fracture 55 of the body 13 connecting the arms 14 and 15 at the inner end of the throat. As a result, such machines are comparatively costly in construction, due to amount of material used, as well as difficult to transport 60 and move from place to place, and therefore costly in this connection, because of their heavy weight. It is therefore a desideratum to provide a machine which, while of ample strength to resist all strains, is at the same 65 time comparatively light in weight and ac-

cordingly cheaper of construction and more readily capable of being transported and moved from place to place as occasion requires. By the provision of the overhead brace or jack 19, which is adjustable to suit 70 varying conditions, the arm 15 is sustained as against the working pressures falling thereon and consequently liability of fracture of the part 13, at the point of union of the two arms 14 and 15, is entirely obviated or reduced to the minimum, enabling 75 a machine of great strength, but light in weight, to be constructed, with resultant economy in many directions.

From the foregoing it is apparent that I 80 have provided an embossing machine of extremely simple construction and which may be easily and properly operated, and danger of spoiling or damaging the work is exceedingly remote. The various adjustments 85 may be quickly and easily made and accurately maintained at all times, and while the above is a description of the invention in its preferred embodiment, it will be understood that variations in the form, size, 90 proportion and arrangement of parts may be resorted to if desired, without departing from the spirit of the invention as defined by the claims.

Having thus fully described my invention, I claim:—

1. In an embossing machine, a frame including upper and lower parallel heads separated by an intervening throat, the upper head having at its forward end a bifurcated 100 portion forming a vertical guideway, a shaft carried by said head and arranged normally parallel with the throat, said shaft being longitudinally adjusted and pivotally mounted at its rear end, a block fitted in 105 the vertical guideway of the upper head and in which the forward end of said shaft is slidably and rotatably mounted, said block having channels in its sides, pins carried by the walls of the guideway and engaging said 110 channels, an adjusting screw mounted on the upper head and swiveled to said block whereby the forward end of the upper shaft may be raised and lowered in the guideway, a lower shaft carried by the lower head and 115 inclined to the plane thereof, said shaft being longitudinally adjustable, embossing rolls upon the forward ends of said shafts, intermeshing gears upon the rear ends of 120 said shafts, and means for driving said gears.

2. In an embossing machine, a frame having upper and lower horizontal heads spaced by an intervening throat, a shaft mounted upon the upper head and pivotally supported at its rear end, means for adjusting the forward end of said shaft toward and from the throat, a shaft carried by the lower head and arranged in an inclined plane, embossing rolls upon the forward ends of said 125 130

41
shafts, intermeshing gears upon the rear ends of said shafts, means for driving said gears, a table supported upon the lower head above the forward end of the inclined shaft, said table being vertically adjustable in the throat and having a slotted offset depending at one side thereof parallel with one side of said head, an adjusting screw on the lower head swiveled to the table whereby said table may be vertically adjusted, a locking pin passing through the slotted offset and engaging a threaded opening in the lower head, and a coiled spring surrounding said pin between said offset and head. 10
In testimony whereof I affix my signature. 15

HENRY WELSCH.
